US0D1101527S

(12) **United States Design Patent** (10) **Patent No.:** **US D1,101,527 S**
(45) **Date of Patent:** **** Nov. 11, 2025**

(54) **FASTENER REMOVAL TOOL**

(71) Applicant: **Terry K Robins**, Minneapolis, KS (US)

(72) Inventor: **Terry K Robins**, Minneapolis, KS (US)

(**) Term: **15 Years**

(21) Appl. No.: **29/960,068**

(22) Filed: **Aug. 28, 2024**

Related U.S. Application Data

(63) Continuation-in-part of application No. 29/949,421, filed on Jun. 26, 2024, and a continuation-in-part of application No. 18/215,138, filed on Jun. 27, 2023, now abandoned.
